CLAIM

We claim the ornamental design for a baseball elbow guard, as shown and described.

DESCRIPTION

FIG. 1 is a perspective view of a baseball elbow guard showing our new design;

FIG. 2 is a front plan view thereof;

FIG. 3 is a rear plan view thereof;

FIG. 4 is a top elevational view thereof;

FIG. 5 is a bottom elevational view thereof;

FIG. 6 is a left side elevational view thereof; and,

FIG. 7 is a right side elevational view thereof.

The portions shown in broken lines show unclaimed subject matter and form no part of the claimed design.
